UNITED STATES PATENT OFFICE.

STEVEN RADIMAK, OF NEW YORK, N. Y.

DOLL-EYE-PAINTING MACHINE.

1,352,528.

Specification of Letters Patent. Patented Sept. 14, 1920.

Application filed March 1, 1920. Serial No. 362,238.

To all whom it may concern:

Be it known that I, STEVEN RADIMAK, citizen of Hungary, resident of New York, in the county of New York and State of New York, have invented certain new and useful Improvements in Doll-Eye-Painting Machines, of which the following is a specification.

This invention relates to machines for applying color to dolls, and especially applicable to machines which are adapted for painting various predetermined parts of the doll.

The object of this invention is the provision of a machine for automatically applying dabs of color of predetermined shape to dolls fed to the machine in order to simulate, in the dolls, the appearance of the various facial features.

To accomplish the aforesaid and other objects, I employ the mechanism shown in its preferred form in the accompanying drawings, in which,

Figure 1 is a plan view of a section of my improved machine.

Fig. 2 is a partial side view and vertical section of the same on line 2—2 of Fig. 4.

Fig. 3 is an enlarged plan view of the same, the fan supporting table having been removed to show the driving mechanism thereunder.

Fig. 4 is a front view and vertical section of the machine on line 4—4 of Fig. 2.

Fig. 5 is a vertical section of the paint fountain and die.

In the practical embodiment of my invention, a number of entirely similar instrumentalities, for applying the color, are employed, only one of which is hereinafter fully described, it being understood that the same description is applicable to all.

A solid frame 1 for the bottom and back of the machine, and solid frames 2 and 2^a for the front and end respectively are shown, but it is obvious that any type of frame suitable for supporting the various parts, such as shafts, bearings, etc., may be used. A source of power, as motor 3, transmits the power through belt 4 to pulley 5, which is mounted on shaft 6 journaled in frames 1 and 2. Bevel gear 7, at one end of said shaft 6, meshes with bevel gear 8 at the end of longitudinally disposed shaft 9. Said shaft 9 may be made of any desired length sufficient to have mounted thereon, in proper space relation, the various cams 10, for oscillating

the color applying dies 11, and is supported from frame 2 by bearings as 12. On shaft 6, between pulley 5 and gear 7, is mounted spur gear 13, which engages gear 14 on shaft 15. The same shaft 15 carries segmental gear 16, which is arranged to mesh with gear 17 on shaft 18, said shaft 18 carrying sprocket wheels 19 by means of which chain belts 20 are driven.

A number of doll carriers 21 are provided to carry the dolls 24 therein, said dolls being held in the same position in each carrier by means of thumb-screws 25 and pads 26 connected thereto, which operate to wedge the doll against the side of hole 46 in said carrier. It is obvious that the shape, either of hole 46, or of the bottom of the doll, may be such that any doll inserted into any of carriers 21 will be held in the same relative position for operation thereon by the painting mechanism. The carriers 21 are propelled in the direction of the arrow in Fig. 1, by means of lugs 27 on rods 28 attached at regular intervals between chains 20, the distance between said rods 28 being sufficient to allow the insertion of a carrier 21 between them. Additional rods 29, similar to rods 28 are provided, to bridge the space between chains 20. A set of wheels 22, preferably four in number, is carried by each of carriers 21 on studs as 30, said wheels being arranged to run in vertically disposed T-slot 23 of frame 1. Said slot is made wider vertically at the outer part than the remainder thereof, to keep said wheels 22 running in the wide track of slot 23 for supporting said carrier 21.

The color applying mechanism comprises a printing die or pad as 11 of the proper size and shape to color any desired facial part as 95 the eyebrows and made preferably of absorbent material of sufficient density to print an accurate patch, a removable die block and ink applicator 31 in which die 11 is held and which spreads ink or paint over die 11 in any suitable manner such as by means of openings 47 leading to pad 11, and ink or paint fountain 32 attached to lever 33, said fountain carrying said die block and die pad, all of which may be of any 100 well known design which provides for the supply of ink or paint from a fountain to a removable printing die.

Lever 33 is pivoted at 34 to lug 35 outstanding from table 36, which is suitably 110 fastened to frame 2. The lower of lever 33 carries roller 37 for engaging cam 10,

spring 38 yieldingly fastening said lever to frame 2, and acting to keep said roller 37 in contact with said cam 10.

A series of fans as 39 on shaft 40 supported by bearing 41 on table 36, is arranged so that said fans are as close as may be necessary for drying the paint between applications thereof to a doll, while the doll is being carried along in the machine. Pulley 42 on the end of shaft 40 is continuously driven from pulley 43 on shaft 9 by means of a belt 44.

The operation of my improved machine is as follows:

15 Doll 24 having been inserted into carriers 21, said carriers are placed, one at a time, with wheels 22 in the wide track of T-slot 23, and bottom of said carriers near to or resting on rods 29 between lugs 27. 20 The proper dies having been placed in blocks 31 and the blocks having been adjusted in the proper fountains 32 by means of swivel plates 50 and tightening screws 51, said fountains are filled with inks or 25 paints (48) of the desired colors, the pressure of which can be regulated by hand-screw 49 through openings 47 to die 11, then the current is switched on to motor 3.

Through the train of gears above described, sprocket wheels 19 and chains 20 are given an intermittent motion, the teeth of segmental gear 16 being so arranged that each impulse drives the chain a distance substantially equal to the width of one of carriers 21. Shaft 9 being rotated through belt 4, pulley 5 and gears 7 and 8, turns cam 10 thereby causing lever 33 and die 11 thereon to be oscillated. Cam 10 is so designed that said die 11 is brought slowly into contact 40 with the doll for a short interval of time, to leave an imprint on said doll of the desired shape and in the desired position to simulate a feature of said doll.

The carrier holding the doll is moved 45 along while the next doll is being brought into painting position, fans 39 operating in

the meantime, to dry the paint. When the next one of dies 11 is reached, another imprint is made on the doll by means of a similar mechanism.

It is obvious that the number of imprints to be made determines the length of the machine. After the coloring has been completed, and the paint dried, the chains 20 convey carriers 21 on to table 45, from 55 which the carriers may be removed, the finished dolls taken out, and the carriers re-loaded for another trip through the machine.

What I claim is:—

1. In a doll painting machine, paint applying means, and means for advancing a doll to said paint applying means, comprising a table, a series of doll carriers resting freely on said table, a pair of endless 65 chains, rods connecting said chains, and lugs on said rods engaging said doll carriers.

2. In a doll painting machine, a frame having a vertical T-slot therein, a doll carrier, wheels on said carrier arranged to run 70 in the wide part of said T-slot for supporting said carrier from said frame, means for intermittently advancing said carrier, and oscillatory means for applying a patch of color to said doll while said doll is at rest. 75

3. In a doll painting machine, a frame having a vertical T-slot therein, a doll carrier, wheels on said carrier arranged to run in the wide part of said T-slot for supporting said carrier from said frame, means for 80 intermittently advancing said carrier, a lever pivoted between its ends, a printing die removably attached to said lever near one end thereof, means for supplying paint to said die, and a cam for coaction with the 85 other end of said lever for oscillating said lever to imprint a patch of color on a pre-determined part of said doll while said doll is at rest.

Signed at New York, in the county of 90 New York and State of New York.

STEVEN RADIMAK.
